UNITED STATES PATENT OFFICE.

CHARLES K. SIMPSON, OF PHILADELPHIA, PENNSYLVANIA.

ROTARY MOTOR AND PUMP.

1,249,527.

Specification of Letters Patent.

Patented Dec. 11, 1917.

Application filed July 31, 1916. Serial No. 112,249.

To all whom it may concern:

Be it known that I, CHARLES K. SIMPSON, a citizen of the United States, residing at Philadelphia, county of Philadelphia, and 5 State of Pennsylvania, have invented certain new and useful Improvements in Rotary Motors and Pumps; and I do hereby declare the following to be a full, clear, and exact description of the invention, such as 10 will enable others skilled in the art to which it appertains to make and use the same.

The invention relates to rotary motors and pumps, involving a piston chamber and a rotary piston head mounted therein provided with sliding pistons which engage the wall of the piston chamber, and the invention has for its object to provide simple and efficient means for introducing pressure behind the sliding pistons to hold the same in 15 fluid-tight contact with the chamber walls. The invention is illustrated in the accompanying drawings, in which:—

Figure 1 is a front elevation of a rotary pump involving the novel features of construction and operation, the front face plate being removed;

Fig. 2 is a longitudinal section on line 2—2 of Fig. 1; and

Fig. 3 is a perspective detail of the sliding pistons.

Referring to the drawings, 1 indicates a generally cylindrical piston chamber provided with a base 2, the body portion of the chamber being preferably of substantially 25 annular form and having a front closure plate 3 attached thereto by screws 4, or the like, and a rear closure plate 5 provided with a rear extension 8 which forms a journal bearing for the shaft carrying the rotor 30 member. Cheek plate 5 is preferably secured to the adjacent face of the body portion 1 by means of bolts 7 which pass through elongated slots 6 which admit of the plate 5 being adjusted vertically with 45 respect to the body portion 1 to compensate for wear.

Formed in the upper portion of the body portion 1 are ports 10 and 11 which serve to admit and exhaust the fluid medium 50 which acts upon or is acted upon by the rotary pistons.

Mounted eccentrically within the piston chamber is a rotary piston head 12, which, as indicated, is tangent to the inner wall of

the piston chamber at the upper portion 55 thereof and said piston head, which is preferably formed as an integral casting, is provided with two stepped shoulders 13, which engage complementary shoulders on the inner face of the face plate 5 and which serve as 60 an efficient means for preventing the escape of fluid pressure through the journal bearing. It will be understood that the lateral faces of the piston head 12 closely engage the inner surfaces of the face plates 3 and 65 5 to form substantially a fluid-tight joint. The piston head is mounted on the end of a shaft 14 journaled in the bearing 8, and said shaft is provided with the usual pulley or gear (not shown) through which 70 power may be applied to or taken from the rotary piston head, as will be understood.

In the form of the apparatus shown, the piston head 12 is provided with a diametrical slot 15, which slot is adapted to receive 75 two radially sliding pistons 16 and 16', each of which is provided at its outer end with a packing strip, 18, 18', of fiber or similar material, which engages the inner wall of the piston chamber 1. The lateral vertical 80 edges of the sliding piston 16, 16' contact with the inner walls of the face plates 3 and 5. In order to insure efficient operation of the machine, whether the same be employed as a fluid pressure motor or as a 85 pump, it is necessary that the outer ends of the sliding pistons be held in fluid-tight contact with the walls of the piston chamber, and to effect this result, each of the pistons 16, 16' is provided with a channel 90 17, 17' running longitudinally through the body thereof and the outer ends of said channels are so proportioned and arranged that when the piston is projected materially beyond the periphery of the rotary piston 95 head, the end of the channel will be gradually uncovered to admit fluid pressure behind the sliding pistons, and as the pistons are retracted or withdrawn within the piston head, the open ends of the channels will 100 be gradually closed, and when finally closed will trap the fluid under pressure therein, so that further relative movement of the sliding pistons will increase the pressure of the entrapped fluid and thereby increase the 105 force with which the sliding pistons are pressed into engagement with the walls of the piston chamber. The combined length

of the pistons 16, 16' is somewhat less than the diameter of the piston chamber 1, so that a space is left between the inner ends of the pistons, which space may be partially 5 filled by a rectangular block 19 of fiber or the like, which is provided with a perforation registering with the channels 17 and 17', and which, therefore, permits the fluid pressure to be applied to the rear of both 10 of the pistons. The channels 17, 17' may be formed in any appropriate manner and, obviously, multiple alining channels may be provided in each piston if such are found necessary and desirable. In the particular 15 form of the channels shown in the exemplary machine, said channels are formed by longitudinal bores having angular end portions which are adapted to be covered and uncovered by the movement of the pistons 20 toward and from the center of the piston head.

The operation of the machine is as follows. Assuming the machine to be employed as a pump for air or other compressible fluid, when rotary motion is imparted 25 to the piston head 12, in the direction of the arrow, the fluid will be drawn in through the inlet 10, following the movement of the right-hand piston 16. Said piston 16, due 30 to the eccentric relation of the piston head 12 and the piston chamber 1, moves outward and during such outward movement, uncovers the end of the channel 17, thereby admitting the pressure on the forward side 35 of the piston into the channels 17 and 17' of the respective pistons, which pressure serves to hold the packing trips 18, 18' firmly against the walls of the piston chamber, and as the rotary motion continues, both pistons 40 are forced inwardly radially of the piston head and the outlet of the channel 17 is closed, thereby trapping the fluid under pressure in the channels of the pistons, and between the inner ends of the pistons, and as 45 said pistons are forced to their ultimate inner positions, as illustrated in full lines in Fig. 1, the pressure of the trapped fluid will be increased somewhat in excess of the pressure on the exhaust side of the pump, thereby 50 insuring a predominance of the pressure tending to force the packing strips of the pistons against the chamber walls. As the pistons and the channels therein are symmetrically disposed with the outlets of the 55 channels opening in opposite directions, it will be obvious that each of the channels is alternately opened and closed by the walls of the slot in the piston head 12, during each revolution of the piston head, so that 60 at all times the pistons are subjected to sufficient pressure to hold the outer ends thereof into fluid-tight engagement with the wall of the piston chamber.

When the apparatus is used as a motor instead of a pump, it is necessary only to either

reverse the relation of the channels in the pistons 16 and 16', or to reverse the arrangement of the inlet and exhaust ports, so that the fluid under pressure entering the motor will enter the channel on the rear face of 70 the intake piston and immediately exercise sufficient pressure on both pistons to force them outwardly, as described, and hold the packing strips 18 firmly in engagement with the chamber walls. 75

What I claim is:—

1. In a machine of the class described, the combination with a piston chamber having inlet and outlet ports, of a rotary piston head mounted eccentrically in said chamber, and pistons slidably mounted in said head and engaging the wall of the chamber, each of said pistons having a channel passing through the body thereof and adapted to communicate with the chamber to admit fluid pressure behind the pistons, said pistons being operable upon the rotation of the piston head to increase said fluid pressure. 80

2. In a machine of the class described, the combination with a piston chamber having inlet and outlet ports, of a rotary piston head mounted eccentrically therein, and pistons slidably mounted in said head and engaging the wall of the chamber, each of said pistons having a channel through the body thereof to admit fluid pressure behind the pistons, the said pistons being simultaneously movable into the piston head to cover 95 said channels whereby the fluid pressure behind the same is increased. 100

3. In a machine of the class described, the combination with a cylindrical piston chamber having inlet and outlet ports, of a rotary piston head mounted eccentrically 105 therein, and pistons arranged diametrically opposite to each other and slidably in said head, said pistons having communicating channels which open adjacent to the outer ends of the pistons, the sliding movement of 110 said pistons being sufficient to move the pistons into the head to such an extent that the channels in the pistons are alternately opened and closed. 115

4. In a machine of the class described, the combination with a cylindrical piston chamber having inlet and outlet ports, of a rotary piston head mounted eccentrically 120 therein, opposed pistons slidably mounted in said head and engaging the wall of the chamber, said pistons having communicating channels therein which open adjacent to the ends of the pistons and are adapted to be alternately covered and uncovered by the head during the rotation of the same, said 125 pistons being simultaneously movable into the piston head to increase the fluid pressure behind the same.

5. In a machine of the class described, the combination with a cylindrical piston cham- 130

ber having inlet and outlet ports, of a rotary piston head mounted eccentrically therein, aligned pistons slidable in said head and engaging the wall of the chamber, each of 5 said pistons having a channel therein, said pistons being movable in the head during its rotation to project the ends of the channels

beyond the face of the piston to admit fluid pressure behind the pistons and movable to simultaneously close the ends of the channels to increase said fluid pressure. 10

In testimony whereof I affix my signature.

CHARLES K. SIMPSON.
